Application April 16, 1936, Serial No. 74,686

20 Claims. (Cl. 122—448)

Our invention relates to improvements of steam generators, and more particularly to steam generators with forced passage of the operating medium.

5 It is an object of our invention to provide a forced-flow tubular steam generator having a zone wherein the working fluid is converted from the liquid to the vapor state located in a portion of the heating space of such relatively low 10 heat intensity that injury to the tubing of the conversion zone will be minimized, even though such tubing may contain salt deposits, together with means responsive to a physical characteristic or characteristics of the working fluid to 15 control application of heat to the generator in such manner as to prevent substantial shifting of the conversion zone, particularly under variable load conditions.

A further object of our invention is to provide 20 a furnace chamber having three heating zones, first, a zone subject mainly to radiant heat, second, a zone subject partly to radiant and partly to contact heat, and, third, a zone subject mainly to contact heat; a tubular system having tubular elements in said zones and so arranged that conversion of the working fluid from the liquid to the vapor state is completed in the tubular element of the third zone and the vapor received from the last-named tubular element is superheated in the tubular element of the second zone; and means responsive to one or more physical 30 conditions of the working fluid for controlling the supply of combustion media to the furnace chamber in such manner as to restrict shifting of said conversion zone.

A further object of our invention is to provide 35 apparatus of the above character wherein the superheater is so located in the furnace that the quantity of heat absorbed per unit of weight is substantially constant under variable load and pressure conditions and means is provided to maintain the outlet temperature of the superheater substantially constant under variable load conditions, these two things, namely, location of the superheater and control of application of heat so as to maintain the superheater outlet 40 temperature substantially constant serving to restrict shifting of the salt-deposit zone, so that creeping of the latter into high temperature 45 regions is prevented.

A further object of our invention is to provide 50 apparatus of the above character wherein the supply of combustion media is controlled by a thermostat responsive to the temperature of superheated working fluid leaving the superheater.

It is, furthermore, an object of our invention to provide apparatus of the above character wherein the supply of combustion media is controlled jointly by means responsive to pressure of working fluid and means responsive to temperature of said fluid supplied to the third tubular element or superheater.

These and other objects are effected by our invention, as will be apparent from the following description and claims taken in connection with the accompanying drawings, forming a part of this application, in which:

Figs. 1 and 2 are diagrams illustrative of thermal principles involved in our invention;

Fig. 3 is a diagrammatic view of a steam generator embodying our improved control system;

Fig. 4 is a fragmentary diagrammatic view showing a second embodiment of our invention; and,

Fig. 5 is a diagram.

In accordance with our invention, we provide a steam generator arrangement with forced passage of the operating medium for carrying out the method as set forth in copending application Serial No. 691,349, filed September 28, 1933, 25 which consists in operating the steam generator, in case of increase in load, with increasing pressure and, in case of decrease in load, with decreasing pressure. In order to carry out this method with apparatus of this character, special 30 provisions must be made so as to ensure reliable and continuous operation of the plant.

To prevent deterioration of the tubes by salt 35 deposits during operation, the heating surfaces of such steam generators, in which evaporation takes place must be, as particularly set forth in copending applications Serial Nos. 655,805 and 690,262, filed February 2, 1933 and September 20, 1933 respectively, subdivided into two different surfaces of different rates of heat impact, i. e., 40 into a heating surface portion (I) of higher heat impact, in which the percentage of liquid of the operating medium with respect to the total extension of the heating surface portion (I) is greater than the percentage of vapor (phase I of the 45 production of steam) and into a second heating surface portion (II) of lower heat impact, in which the percentage of vapor is greater than the percentage of liquid (phase II of the production of steam). The first superheating surface portion (III), next to the surface of evaporation, in which portion the vapor is superheated to a given degree (phase III of the production of steam), also forms preferably a heating surface portion of lower heat impact, that is to 50

say, the heating surface portion I should be disposed in a radiation heating chamber and the heating surface portions II and III in a contact heating chamber.

5 It is apparent that the position of the phases of steam production are not fixed, if the operation of the system is radically changed as provided for in carrying out the method as set forth in the first aforesaid copending application, i. e., 10 if the operating pressure varies with varying load of the boiler. The object of the present invention is to provide means whereby it is possible that said phases II and III—the position of which is above all essential during operation—adjust 15 themselves continuously within the predetermined heating surface portions II and III independently of fluctuations of pressure and load.

Since phase II ends upon the attainment of the state of dry saturation characterized by the upper limit curve of the heat-temperature diagram and since phase III begins upon the attainment of said state, it is practically sufficient to initiate, if possible, the generation of steam in such a manner that this state adjusts itself in operation continuously at the same region of the heating surface.

To prevent shifting of said region or the zone where change of state is completed, two measures are proposed according to the invention. The 30 first measure consists in maintaining the temperature of superheat constant independently of the pressure. In applying this measure, determinations at different operating pressures are made with the aid of the diagram Fig. 1 (Mollier diagram), which shows the quantity of heat in 35 calories required to superheat a kilogram of steam to a constant temperature of superheat, for instance, of 400° C.; and, if these values are plotted against pressure, the diagram of Fig. 2 is 40 obtained. The latter diagram indicates that the heat of superheat per kilogram of steam with a constant temperature of superheat is sufficiently constant within wide pressure limits. Consequently, if the superheater is arranged in such 45 a manner that it always takes up per kilogram of steam the same quantity of heat, the state of dry saturation with a constant temperature of superheat must necessarily be always obtained at the same point of the heating surface.

50 The second measure consists in inserting in the path of the flue gas the superheater at a point where the absorption of heat per kilogram of steam always remains actually the same. If a steam generator, with a heating surface in a 55 radiation heating chamber and a heating surface in a contact heating chamber, is assumed, and, if the load of the generator is increased, the absorption of heat of the contact heating surface per kilogram of steam increases, whereas the 60 absorption of heat of the radiation heating surface per kilogram of steam decreases. The reverse is the case with a decrease of load. It is apparent that there is a point in the path of the flue gas in each steam generator at which 65 fluctuations of load have no influence upon the absorption of heat per kilogram of steam.

The second measure, to be simultaneously applied with the first in solving the problem consists, therefore, according to the invention in the 70 fact that the superheater is inserted in the path of the flue gas at a neutral point. By simultaneously applying both measures, it is, consequently, possible to maintain the position of the zone, in which the state of dry saturation occurs always 75 at the same point of the heating surface.

As above stated, the phase of production of steam III as well as phase II should adjust themselves within the contact heating surface. Phase III lasts from the beginning of the superheating up to a certain degree of superheating. Referring 5 again to the diagram of Fig. 1, that would mean that the phase III of the generation of steam at a pressure of 60 atmospheres ends, for instance, at the point A. This point lies about 16 units of heat above the corresponding point of the upper 10 limit curve (line a). These 16 units of heat are, consequently, taken up by a contact heating surface, whereas the remaining 110 units of heat (line b) will be taken up by the next superheater disposed at the above-mentioned point. This 15 quantity of 110 units of heat is to be supplied if the superheating is continued up to 450° C. and maintained constant at this temperature. Since the absorption of heat of the superheater per kilogram of steam remains always constant in 20 operation on account of its being arranged in the path of the flue gas at the neutral point, the point A at a pressure of, for instance, 225 atmospheres would correspond to the point B. This 25 point B is obtained by drawing from point B₁ a line c equal to line b. If the values for different pressures and temperatures of superheat are plotted in a corresponding manner the curves 1 and 2 will be obtained. The design of the heating surfaces must be carried out according to 30 these curves in such a manner that the curve to be obtained at different pressures should have the desired minimum distance (a) in units of heat from the upper limit curve in the case of the lowest pressure and of the lowest temperature 35 of feed water. If the point B is taken first, measured a distance a above the upper limit curve, it will be obvious that the line or curve I in the direction of A would enter the region of wet steam. The latter condition must be avoided 40 and this is done by starting with a point such as A located on the lowest pressure line. If the minimum distance a would not be fixed at the lowest inlet temperature of the feed water, it may also happen that the curve upon a decrease of 45 the inlet temperature of the feed water during the operation wanders later in part or wholly into the zone of the wet steam.

As it is necessary with a boiler of the present 50 type to maintain the temperature of superheat constant, we have a thermostat subject to the outlet temperature of the superheater and controlling the supply of combustion media to the furnace chamber in such manner that the temperature of the superheated steam is maintained 55 substantially constant, it being remembered that, referring to the aforesaid description and to Figs. 1 and 2, the heat absorbed per pound of steam is substantially constant over a wide range of pressure and load conditions. Accordingly, if the heat supplied to the generator is so controlled as to keep the superheat temperature substantially constant, and the superheater is so located in the furnace that the quantity of heat absorbed per pound of steam passing 60 through the superheater remains the same over a wide load range, it will be apparent that thermal conditions of the working fluid in tubular elements of the generator immediately preceding 65 the superheater will be such as to restrict or limit shifting of the conversion zone and, therefore, of the salt-deposit zone. While this method of control is sufficient to prevent substantial shifting of the conversion zone, with load fluc- 70 75

tuations, nevertheless, it is subject to the objection of fluctuations caused by delay or lag. For example, if the temperature of the superheated steam should drop and if the control apparatus is, in consequence, adjusted to supply an increased quantity of combustion media, the temperature of the superheated steam would, after a time, be increased at the outlet of the superheater, but, in the meantime, a large quantity of heat is consumed in heating the various boiler parts. Also, when the temperature of the outgoing superheated steam tends to exceed the predetermined temperature, a time lag is introduced before the predetermined superheater temperature is held at normal value by control of the combustion media. We prefer to avoid lag difficulties of this nature and consequent fluctuations due thereto by arranging the thermostat so as to respond to the temperature existing in front of the superheater; however, in this case, as will be apparent from Fig. 1, the temperature should not be regulated to a constant value, as in the case where the thermostat responds to the temperature of superheated steam, but temperatures corresponding to different pressures must be maintained and which are prescribed by the behavior of curves 1 or 2 of Fig. 1. Consequently, if the regulating impulse for control is taken from a point in front of the superheater, whose outlet is to be maintained at 450° C., the control apparatus must regulate the supply of combustion media so as to maintain a temperature of 305° C. in front of the superheater at a pressure of 80 atmospheres, a temperature of 330° C. at a temperature of 120 atmospheres, and a temperature of 355° C. at a pressure of 160 atmospheres, these temperatures for these particular loads being determined from curve 1 of Fig. 1.

In order that the temperature impulses derived from a thermostat located in front of the superheater may be utilized to give results corresponding to temperatures related to the pressures, as indicated by curve 1 of Fig. 1, it is necessary to use a pressure impulse in conjunction with the temperature impulse, the two impulses working together to secure control such that the thermostat is compensated to secure the proper operation for variable load conditions.

If variation in feed water temperature should be a disturbing factor, then an impulse may be provided and dependent on feed water temperature, this impulse being used in conjunction with the temperature impulse in front of the superheater and the pressure impulse of the working fluid to control the application of heat to the boiler so as to maintain the outlet temperature of the superheater substantially constant.

To summarize in general, in all forms of the invention, location of the superheater so as to absorb substantially the same quantity of heat per unit of weight of working fluid passing therethrough and being superheated is essential, for, with this feature, the control apparatus may be controlled by the various temperature and pressure characteristics pointed out in order to maintain the outlet temperature of the superheater substantially constant, the condition of constancy of the superheater outlet temperature and location of the superheater providing for such thermal, and working fluid state conditions in tubular elements of the boiler preceding the superheater that the salt deposit zone may be held within narrow limits and consequently

shifting of that zone into portions of heating space of relatively high heat intensity may be avoided under a wide range of loads.

In Fig. 3, we show an embodiment of our invention wherein the furnace 10 is provided with a chamber 11 having a first zone, at 12, heated mainly by radiant heat, a second zone, at 13, heated partly by radiant heat and partly by contact or convection heat, and a third or convection zone, at 14, heated mainly by contact. Combustion media, for example, fuel and air, are supplied in a regulated manner by the apparatus including a motor 16 for delivering fuel and a motor 17 for delivering air.

The steam generator comprises a tubular system including a first tubular element 18, a second tubular element 19, and a third tubular element 20, the element 18 being located in the first zone 12, the element 19 in the third zone 14, and the element 20 in the second zone 13.

As heretofore pointed out, the phase I of steam generation occurs in the first tubular element, at 18, and the phases II and III of steam generation occur in the second tubular element 19, phase II of steam generation representing the completion of conversion from the liquid to the vapor state, and phase III representing superheating. After leaving the tubular element 19 with the relatively small amount of superheat, the vapor goes to the tubular element 20 where it is superheated.

As heretofore pointed out, and as will be apparent from Fig. 1, the amount of heat absorbed per pound of steam in carrying out the superheating of phase III is kept at a minimum, the object being, as hereinbefore stated, to locate the lines 1 or 2, as the case may be, of Fig. 1, in such manner that, in operating over a wide pressure range, the control apparatus will not be subject to the temperature of wet steam.

In Fig. 3, we show the tubular system supplied with water as working fluid by means of a pump 22, the working fluid flowing once through the tubular system and undergoing the physical changes just indicated. The pressure of working fluid is due entirely to said pump 22.

As pointed out in the aforesaid application, Serial No. 691,439, variable-pressure cycle operation of the plant may be secured by having the feed pump responsive to a load effect such as speed, that is, with an increase in load, the feed pump is controlled to increase the pressure of working fluid and vice versa. To this end, in Fig. 3, we show the tubular system of the steam generator supplying superheated steam to the turbine 23, having a governor 24 which controls the speeds of the motors 25, 16, and 17 supplying feed water, fuel, and air respectively, to the boiler.

As pointed out in said application, Serial No. 691,439, feed water, fuel and air are supplied in such manner as to secure steam delivery from the boiler at a pressure dependent upon the load. Also, irrespective of operating pressure, the outgoing steam temperature is held constant. Accordingly, we show a thermostat 28, which exerts a correcting influence on the fuel and air supply motors 16 and 17 in such manner that the latter operate to secure the heat release required to keep the temperature of steam approximately constant.

By way of example, we show the thermostat 28 operatively associated with contacts, at 29, controlling the reversible motor 30 for operating the rheostat 31 in the circuits of the motors 16 and 17.

17. As already indicated, the governor 24 controls the speeds of the feed water motor 25, the fuel supply motor 16, and the air supply motor 17, whereby, incident to load change, the feed pump speed is changed to change the operating pressure and the fuel and air supply motors have their speeds changed in a direction generally suitable to the change in feed water supply. For example, we show the governor 24 operatively associated with the rheostat 24a in the circuits of the motors. In order that a predetermined outgoing superheat temperature may be maintained, it is necessary to apply a correcting influence to the supplies of fuel and air; and, for this reason, the thermostat 28 is employed for controlling the fuel and air supply motors 16 and 17.

As hereinbefore indicated, to avoid lag effects and consequent shifting of the conversion zone, additional controlling elements are employed. In Fig. 3, a thermostat 31 is arranged in front of the superheater 20 and a pressure responsive device 32 is associated with the tubular series-flow passage, the thermostat and the pressure responsive device operating in any suitable manner to impose an additional controlling effect on the reversible motor. One example of a way in which the thermostat and the pressure responsive device may be used for this purpose is shown diagrammatically in Fig. 3 wherein the thermostat 31 is operatively connected to the responsive element 33, and the pressure responsive device to the responsive element 34. The responsive elements 33 and 34 have their movements transmitted in any suitable manner to the contacts, at 29, for controlling the reversible motor.

In Fig. 4, there is shown an arrangement similar to Fig. 3 except that there is an additional temperature impulse used, a thermostat 36 being associated with the series-flow tubular surface 40 in front of the surface 18 and sensitive to feed water temperature changes. The thermostat 36 operates an element 33, which, in conjunction with the elements 37 and 34 serve to control the contacts, at 29.

45 Thus, it will be seen that, in Figs. 3 and 4, thermostats are employed which minimize lag difficulties and limit shifting of the conversion zone, because such thermostats are sensitive to temperature changes in advance of the thermostat 28.

As hereinbefore indicated, an important feature of the present invention is location of the superheater, it being necessary that it shall be so located as to absorb substantially the same quantity of heat per unit of weight of vapor passing therethrough and being superheated under variable load conditions, variation in load, of course, introducing variation in pressure. With the variable pressure cycle of operation, the quantity of radiant heat absorbed per unit of weight of motive fluid being superheated diminishes with increase in load and pressure and vice versa. This is indicated diagrammatically in Fig. 5 by the curve R. On the other hand, the quantity of contact heat absorbed per unit of weight of working fluid being superheated increases with increase in load and pressure and vice versa, this being indicated by the curve C on Fig. 5. Accordingly, the superheater is so located in the heating space as to be subject both to radiant and to contact heat so that it has a neutral location insofar as absorption of heat per unit of weight under varying load conditions is concerned. In other words, irrespective of variations in load and pressure, the heat absorbed per unit of weight of vapor passing through the superheater

and being superheated is substantially constant. With such location of the superheater and with control of the application of heat so as to maintain the superheater outlet temperature substantially constant, it will be apparent that means are provided to restrict shifting of the salt deposit zone, for these conditions impose such thermal conditions on the working fluid that the conversion zone of the boiler is held within fairly narrow limits under variable load and pressure conditions. 5

In connection with Figs. 3 and 4, it will be apparent that the thermostat and pressure control devices may be used in any suitable manner to bring about adjustments in fuel and air supplies. To this end, and by way of example, in Fig. 3, we show the actuated elements 33 and 34 connected to the ends of a floating lever 40 operatively connected, through a dash pot at 41, to one end of the lever 42, the other end of the latter lever carrying a contact 43 arranged between the contacts 44 and 45 of the contact device, at 29. As shown, the contacts 44 and 45 are positioned in response to the thermostat 28. The lever 42 tends to be maintained in a central position by means of springs 46, movement of the lever for this purpose being provided by the dash pot, as the dash pot has suitably small openings 47 in its piston which cause the dash pot to function as a link to transmit motion of the elements 33 and 34 to the contact 43, but which permit of relatively slow movement of restoration of the lever 42 to central position. With this arrangement, it will be apparent that the thermostat 28 controls the contacts 44 and 45 so as to secure supplies of fuel and air in such a manner as to maintain the outgoing steam temperature approximately constant. Also, the thermostat 31 and the pressure responsive device 32 operate through the intermediary of suitable mechanism to control the contacts in such manner as to minimize lag effects. The operation of the apparatus shown in Fig. 4 is similar except that an additional temperature impulse is taken into account.

From the foregoing, it will be apparent that we have devised a steam generator of the series-flow type wherein the operating pressure is dependent upon the feed pump and the turbine governor is employed to control, not only the feed pump, but also the supplies of fuel and air. A correction impulse is derived from the thermostat 28 associated with the outgoing steam line to control supplies of fuel and air so as to maintain the outgoing steam temperature approximately constant. With this arrangement of devices, providing a variable pressure steam generator arranged to supply steam at approximately constant temperature irrespective of pressure, it is desirable to incorporate the aforementioned features of control to minimize shifting of the conversion zone, such measures of control being the location of the superheater 20 in such manner as to absorb the same quantity of heat per pound of steam at different loads and the features which operate to give an anticipating effect, the latter features including the thermostat 31 and the pressure responsive device 32 of Figs. 3 and 4 as well as the thermostat 36 of Fig. 4 and these devices providing for relatively quick response and reduction in lag. In other words, the location of the superheater and the supplementary and anticipatory controlling devices cooperate to keep the conversion zone restricted to relatively narrow limits irrespective of

operation of the boiler under variable load conditions.

While we have shown our invention in two forms, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

What we claim is:

1. In a generator supplied with liquid as working fluid and transforming it into superheated vapor, a furnace chamber including a contact heat zone and a combined radiant and contact heat zone, a tubular system comprising tubular heat-absorbing elements arranged in said chamber and including tubular heat-absorbing elements in said zones, means for securing forced flow of working fluid through the tubular system and under pressure depending upon the load, the tubular heat-absorbing element or elements preceding in the direction of working fluid flow the element in the contact zone and the latter being so arranged and heat being so absorbed thereby that the solid or scale-deposit zone due to conversion of the working fluid from the liquid to the vapor state is located in tubing of the element in the contact zone subject to heat of such relatively low intensity that injury to such tubing will be minimized even though it contains solid or scale-deposits and the tubular element in said combined radiant and contact heat zone serving to superheat vapor received from the tubular element in the contact zone, and means for restricting shifting of said solid or scale-deposit zone including the tubular heat-absorbing element so located in the combined radiant and contact heat zone that the quantity of heat absorbed per unit of weight of vapor passing through and being superheated is substantially constant under variable load conditions.

2. In a generator supplied with liquid as working fluid and transforming it into superheated vapor, a furnace chamber including a contact heat zone and a combined radiant and contact heat zone, a tubular system comprising tubular heat-absorbing elements arranged in said chamber and including tubular heat-absorbing elements in said zones, means for securing forced flow of working fluid through the tubular system and under pressure depending upon the load, the tubular heat absorbing element or elements preceding in the direction of working fluid flow the element in the contact zone and the latter being so arranged and heat being so absorbed thereby that the solid or scale-deposit zone due to conversion of the working fluid from the liquid to the vapor state is located in tubing of the element in the contact zone subject to heat of such relatively low intensity that injury to such tubing will be minimized even though it contains solid or scale-deposits and the tubular element in said combined radiant and contact heat zone serving to superheat vapor received from the tubular element in the contact zone, and means for restricting shifting of said solid or scale-deposit zone including the location of the tubular heat absorbing element in the combined radiant and contact heat zone in such manner that the quantity of heat absorbed per unit of weight of vapor passing therethrough and being superheated is substantially constant under variable load conditions

and means for controlling the application of heat to the heat-absorbing elements of the generator so as to maintain the temperature of superheated vapor leaving the generator substantially constant.

3. In a motive fluid generator, a furnace having a heating chamber including a first zone wherein heating occurs due mainly to radiation, a second zone wherein heating occurs partly due to radiation and partly due to contact or convection, and a third zone wherein heating occurs mainly due to convection; a tubular system including first, third, and second tubular elements arranged in said first, second, and third zones, respectively, and the first, second, and third tubular elements being connected in series; means for supplying liquid as working fluid to the tubular system for forced flow therethrough under pressure depending upon the load; the first and second tubular elements being constructed and arranged so that the solid or scale-deposit zone due to conversion of the working fluid from the liquid to the vapor state is located in tubing of the second tubular element arranged in a part of said third zone of such relatively low heat intensity that injury to such tubing will be minimized even though containing deposits of solids or scale; and means for restricting shifting of said solid or scale-deposit zone including the location of said third tubular element functioning as a superheater in such manner that the quantity of heat absorbed per unit of weight of vapor passing therethrough and being superheated is substantially constant under variable load conditions and means for controlling the application of heat to the tubular elements so as to maintain the temperature of superheated vapor leaving the third tubular element substantially constant.

4. In a motive fluid generator, a furnace having a heating chamber including a first zone wherein heating occurs due mainly to radiation, a second zone wherein heating occurs partly due to radiation and partly due to contact or convection, and a third zone wherein heating occurs mainly due to convection; a tubular system including first, third, and second tubular elements arranged in said first, second, and third zones, respectively, and the first, second, and third tubular elements being connected in series; means for supplying liquid as working fluid to the tubular system for forced flow therethrough under pressure depending upon the load; the first and second tubular elements being constructed and arranged so that the solid or scale-deposit zone due to conversion of the working fluid from the liquid to the vapor state is located in tubing of the second tubular element arranged in a part of said third zone of such relatively low heat intensity that injury to such tubing will be minimized even though containing deposits of solids or scale; and means for restricting shifting of said solid or scale-deposit zone including the location of said third tubular element functioning as a superheater in such manner that the quantity of heat absorbed per unit of weight of vapor passing therethrough and being superheated is substantially constant under variable load conditions and mechanism for maintaining the temperature of superheated vapor leaving the third element substantially constant, said mechanism including means responsive to the temperature of vapor supplied to the third tubular element and to the pressure of working fluid for

controlling the application of heat to the tubular elements.

5. In a steam generator, a furnace having a heating chamber including a first zone wherein heating occurs due mainly to radiation, a second zone wherein heating occurs partly due to radiation and partly due to contact or convection, and a third zone wherein heating occurs mainly due to convection; a tubular system including first, third, and second tubular elements arranged in said first, second, and third zones, respectively, and the first, second, and third tubular elements being connected in series; means for supplying liquid as working fluid to the tubular system for forced flow therethrough under pressure depending upon the load; the first and second tubular elements being constructed and arranged so that the solid or scale-deposit zone due to conversion of the working fluid from the liquid to the vapor state is located in tubing of the second tubular element arranged in a part of said third zone of such relatively low heat intensity that injury to such tubing will be minimized even though containing deposits of solids or scale; and means for restricting shifting of said solid or scale-deposit zone including the location of said third tubular element functioning as a superheater in such manner that the quantity of heat absorbed per unit of weight of vapor passing therethrough and being superheated is substantially constant under variable load conditions, means providing an impulse depending upon the temperature of vapor supplied to the third tubular element, means providing an impulse depending upon the temperature of vapor leaving the third tubular element, means providing an impulse depending upon the pressure of working fluid, and means for utilizing said impulses to control the application of heat to the tubular elements.

6. In a steam generator, a furnace having a heating chamber including a first zone wherein heating occurs due mainly to radiation, a second zone wherein heating occurs partly due to radiation and partly due to contact or convection, and a third zone wherein heating occurs mainly due to convection; a tubular system including first, third, and second tubular elements arranged in said first, second, and third zones, respectively, and the first, second, and third tubular elements being connected in series; means for supplying liquid as working fluid to the tubular system for forced flow therethrough under pressure depending upon the load; the first and second tubular elements being constructed and arranged so that the solid or scale-deposit zone due to conversion of the working fluid from the liquid to the vapor state is located in tubing of the second tubular element arranged in a part of said third zone of such relatively low heat intensity that injury to such tubing will be minimized even though containing deposits of solids or scale; and means for restricting shifting of said solid or scale-deposit zone including the location of said third tubular element functioning as a superheater in such manner that the quantity of heat absorbed per unit of weight of vapor passing therethrough and being superheated is substantially constant under variable load conditions, means providing a first impulse depending upon the temperature of vapor supplied to the third tubular element, means providing a second impulse depending upon the temperature of the liquid supplied to the first tubular element, means providing an

impulse depending upon the temperature of working fluid leaving the third tubular element, means providing an impulse depending upon the pressure of the working fluid, and means utilizing said first, second, third and fourth impulses to control the application of heat to the tubular heat absorbing elements.

7. In a steam generator, a furnace having a heating chamber including a combustion space; a tubular system including first, second, and third tubular elements arranged in said chamber and connected in series, means for supplying water as working fluid to the tubular system and for securing forced flow through the latter of the working fluid; means responsive to the load condition of the generator for causing the pressure thereof to increase with increase in load and vice versa; the first tubular element being arranged in said combustion space, the first and second tubular elements being constructed and arranged so that the salt deposit zone due to conversion of the working fluid from the liquid to the vapor state is in tubing of the second element located in a portion of said chamber of such relatively low heat intensity that injury to such tubing containing salt deposits will be minimized, and the third tubular element being arranged in said chamber so as to absorb heat and superheat the vapor delivered thereto by the second element, combustion apparatus for the combustion space; means for supplying combustion media to the combustion apparatus; and means for controlling the last-named means to vary the rate of supply of combustion media so that the temperature of the superheated working fluid leaving the third element may be maintained substantially constant.

8. In a steam generator, a furnace having a heating chamber including a first zone wherein heating occurs due mainly to radiation, a second zone wherein heating occurs partly due to radiation and partly due to contact or convection, and a third zone wherein heating occurs mainly due to convection; a tubular system including first, third, and second tubular elements arranged in said first, second, and third zones, respectively, and the first, second, and third tubular elements being connected in series; means for supplying water as working fluid to the tubular system and for securing the forced flow through the latter of the working fluid; means responsive to the load condition of the generator for causing the pressure thereof to increase with increase in load and vice versa; the first and second tubular elements being constructed and arranged so that the salt deposit zone due to conversion of the working fluid from the liquid to the vapor state is located in tubing of the second tubular element arranged in a part of said third zone of such relatively low heat intensity that injury to such tubing containing salt deposits will be minimized; combustion apparatus for the first zone of the heating chamber; means for supplying combustion media to the combustion apparatus; and means controlling the last-named means so that combustion media is supplied to the combustion apparatus in such manner that the superheated working fluid leaving the third tubular element is maintained at substantially constant temperature under variable load conditions.

9. In a steam generator, a furnace having a heating chamber including a first zone heated mainly by radiant heat, a second zone heated partly by radiant and partly by contact heat, and

a third zone heated mainly by contact; a tubular system including first, third, and second tubular elements arranged in said first, second, and third zones, respectively; means for supplying water as working fluid to the tubular system and securing forced flow through the latter of the working fluid; means providing for variation in the pressure of the working fluid in accordance with the load; the first and second tubular elements being constructed and arranged so that the salt deposit zone due to conversion of the working fluid from the liquid to the vapor state is located in tubing of the second element in a part of said third zone of such relatively low heat intensity that injury to such tubing containing salt deposits will be minimized, and the third tubular element serving to superheat vapor delivered thereto by the second tubular element; combustion apparatus for said first zone, means for supplying combustion media to the combustion apparatus; said third tubular element being so located in the second zone that the heat absorbed per unit weight of steam passing therethrough is substantially constant under variable load conditions; and mechanism including means responsive to temperature of the working fluid in the vapor state and to pressure of the working fluid for controlling the combustion media supply means so as to keep the temperature of steam leaving the third tubular element substantially constant.

10. In a steam generator of the series-flow tubular type for supplying steam under variable pressure, a feed pump for supplying water to the generator and determining the operating pressure; means for supplying fuel and air to the generator; controlling means for the feed pump operating in response to load to provide a pump outlet pressure which increases with increase of load and vice versa; and thermostatically controlled means including a thermostat associated with the generator outlet steam line for controlling the fuel and air supply means to maintain the outlet steam temperature approximately constant.

11. In a steam generator of the series-flow tubular type and including a superheater for supplying superheated steam under pressure which varies depending upon the load, a feed pump for supplying water to the generator and determining the operating pressure; means for supplying fuel and air to the generator; controlling means for the feed pump operating in response to load to supply feed water under pressure which increases with increase in load and vice versa; a first thermostat associated with the outlet steam line for controlling the fuel and air supply means to maintain the outlet steam temperature approximately constant; and a second thermostat associated with the tubular surface of the generator ahead of the superheater for exerting an additional controlling effect upon the fuel and air supply means.

12. In a steam generator, a furnace chamber including a radiant heat zone, a combined radiant and contact heat zone, and a contact heat zone; a series-flow tubular system including a first heating surface in the radiant zone, a second heating surface in the contact zone, and a third heating surface in the combined radiant and contact zone; a feed pump for supplying water as operating medium for passage through the first, second, and third heating surfaces in series; means for supplying fuel and air to the radiant zone for combustion therein; said first,

second, and third heating surfaces being constructed and arranged so that vaporization is completed in said second heating surface and superheating is effected in said third heating surface; driving means for the feed pump and the fuel and air supply means; and means for controlling said driving means and including means responsive to the temperatures of medium leaving the second and third heating surfaces and to the operating pressure of the medium for exerting a controlling effect on the driving means for the fuel and air supply means.

13. In a steam generator, a furnace chamber including a radiant heat zone, a combined radiant and contact heat zone, and a contact heat zone; a series-flow tubular system including a first heating surface in the radiant zone, a second heating surface in the contact zone, and a third heating surface in the combined radiant and contact zone; a feed pump for supplying water as operating medium for passage through the first, second, and third heating surfaces in series; means for supplying fuel and air to the radiant zone for combustion therein; said first, second, and third heating surfaces being constructed and arranged so that vaporization is completed in said second heating surface and superheating is effected in said third heating surface; driving means for the feed pump and the fuel and air supply means; and means for controlling the driving means for the fuel and air supply means in response to the temperature of medium ahead of and after the superheater and to pressure of the operating medium.

14. In a steam generator, a furnace chamber including a radiant heat zone, a combined radiant and contact heat zone, and a contact heat zone; a series-flow tubular system including a first heating surface in the radiant zone, a second heating surface in the contact zone, and a third heating surface in the combined radiant and contact zone, a feed pump for supplying water as operating medium for passage through the first, second, and third heating surfaces in series; means for supplying fuel and air to the radiant zone for combustion therein; said first, second, and third heating surfaces being constructed and arranged so that vaporization is completed in said second heating surface and superheating is effected in said third heating surface; driving means for the feed pump and the fuel and air supply means operating in response to load to provide steam under pressure which increases with increase in load and vice versa; and means for controlling the driving means for the fuel and air supply means in response to the temperatures existing at separated points ahead of and after the superheater and in response to the operating pressure.

15. In a steam generator, a furnace chamber including a radiant heat zone, a combined radiant and contact heat zone, and a contact heat zone; a series-flow tubular system including a first heating surface in the radiant zone, a second heating surface in the contact zone, and a third heating surface in the combined radiant and contact zone, a feed pump for supplying water as operating medium for passage through the first, second, and third heating surfaces in series; means for supplying fuel and air to the radiant zone for combustion therein; said first, second, and third heating surfaces being constructed and arranged so that vaporization is completed in said second heating surface and superheating is effected in said third heating surface; driving means

- for the feed pump and the fuel and air supply means operating in response to load to provide steam under pressure which increases with increase in load and vice versa; means responsive to temperature of superheated steam leaving the generator for controlling the driving means for the fuel and air supply means so as to maintain the outgoing steam temperature approximately constant; and additional means for controlling the driving means for the fuel and air supply means in response to temperature of water supplied to the first heating surface, to the temperature of medium passing from the second heating surface to the third heating surface and to the pressure of operating medium.

16. In a steam generator, a furnace chamber including a radiant heat zone, a combined radiant and contact heat zone, and a contact heat zone; a series-flow tubular system including a first heating surface in the radiant zone, a second heating surface in the contact zone, and a third heating surface in the combined radiant and contact zone, a feed pump for supplying water as operating medium for passage through the first, second, and third heating surfaces in series; means for supplying fuel and air to the radiant zone for combustion therein; said first, second, and third heating surfaces being constructed and arranged so that vaporization is completed in said second heating surface and superheating is effected in said third heating surface; driving means for the feed pump and the fuel and air supply means operating in response to load to provide steam under pressure which increases with increase in load and vice versa; means responsive to temperature of superheated steam leaving the generator for controlling the driving means for the fuel and air supply means so as to maintain the outgoing steam temperature approximately constant; and additional means for controlling the driving means for the fuel and air supply means in response to temperature of medium ahead of said third heating surface and to the pressure of medium.

17. In a motive fluid generator, a furnace having a heating chamber including a first zone wherein heating occurs due mainly to radiation, a second zone wherein heating occurs partly due to radiation and partly due to contact or convection, and a third zone wherein heating occurs mainly due to convection; a tubular system including first, third, and second tubular elements arranged in said first, second, and third zones, respectively, and the first, second, and third tubular elements being connected in series; means for supplying water as working fluid to the tubular system for forced flow therethrough; the first and second tubular elements being constructed and arranged so that the solid or scale-deposit zone due to conversion of the working fluid from the liquid to the vapor state is located in tubing of the second tubular element arranged in a part of said third zone of such relatively low heat intensity that injury to such tubing will be minimized even though containing deposits of solids or scale; and means for restricting shifting of said solid or scale-deposit zone including the location of said third tubular element functioning as a superheater in such manner that the quantity of heat absorbed per unit of weight of vapor passing therethrough and being superheated is substantially constant and means for controlling the application of heat to the tubular elements and responsive to the temperature of superheated working fluid and to a temperature of the working fluid ahead of the superheater.

18. In a motive fluid generator, a furnace having a heating chamber including a first zone wherein heating occurs due mainly to radiation, a second zone wherein heating occurs partly due to radiation and partly due to contact or convection, and a third zone wherein heating occurs mainly due to convection; a tubular system including first, third, and second tubular elements arranged in said first, second, and third zones, respectively, and the first, second, and third tubular elements being connected in series; means for supplying water as working fluid to the tubular system for forced flow therethrough; the first and second tubular elements being constructed and arranged so that the solid or scale-deposit zone due to conversion of the working fluid from the liquid to the vapor state is located in tubing of the second tubular element arranged in a part of said third zone of such relatively low heat intensity that injury to such tubing will be minimized even though containing deposits of solids or scale; and means for restricting shifting of said solid or scale-deposit zone including the location of said third tubular element functioning as a superheater in such manner that the quantity of heat absorbed per unit of weight of vapor passing therethrough and being superheated is substantially constant and means for controlling the application of heat to the tubular elements and responsive to the temperatures of working liquid between the second and third tubular elements and following the third tubular element.

19. In a motive fluid generator, a furnace having a heating chamber including a first zone wherein heating occurs due mainly to radiation, a second zone wherein heating occurs partly due to radiation and partly due to contact or convection, and a third zone wherein heating occurs mainly due to convection; a tubular system including first, third, and second tubular elements arranged in said first, second, and third zones, respectively, and the first, second, and third tubular elements being connected in series; means for supplying water as working fluid to the tubular system for forced flow therethrough; the first and second tubular elements being constructed and arranged so that the solid or scale-deposit zone due to conversion of the working fluid from the liquid to the vapor state is located in tubing of the second tubular element arranged in a part of said third zone of such relatively low heat intensity that injury to such tubing will be minimized even though containing deposits of solids or scale; and means for restricting shifting of said solid or scale-deposit zone including the location of said third tubular element functioning as a superheater in such manner that the quantity of heat absorbed per unit of weight of vapor passing therethrough and being superheated is substantially constant and means for controlling the application of heat to the tubular elements and responsive to the temperature of feed water supplied to the first element, the temperature of working fluid passing from the second to the third tubular elements and to the temperature of working fluid leaving the third tubular element.

20. In a motive fluid generator, a furnace having a heating chamber including a first zone wherein heating occurs due mainly to radiation, a second zone wherein heating occurs partly due to radiation and partly due to contact or convection, and a third zone wherein heating occurs mainly due to convection; a tubular system including first, third, and second tubular elements arranged in said first, second, and third zones, respectively, and the first, second, and third tubular elements being connected in series; means for supplying water as working fluid to the tubular system for forced flow therethrough; the first and second tubular elements being constructed and arranged so that the solid or scale-deposit zone due to conversion of the working fluid from the liquid to the vapor state is located in tubing of the second tubular element arranged in a part of said third zone of such relatively low heat intensity that injury to such tubing will be minimized even though containing deposits of solids or scale; and means for restricting shifting of said solid or scale-deposit zone including the location of said third tubular element functioning as a superheater in such manner that the quantity of heat absorbed per unit of weight of vapor passing therethrough and being superheated is substantially constant and means for controlling the application of heat to the tubular elements and responsive to the temperature of superheated working fluid and to a temperature of the working fluid ahead of the superheater.

mainly due to convection; a tubular system including first, third, and second tubular elements arranged in said first, second, and third zones, respectively, and the first, second, and third tubular elements being connected in series; means for supplying water as working fluid to the tubular system for forced flow therethrough; the first and second tubular elements being constructed and arranged so that the solid or scale-deposit zone due to conversion of the working fluid from the liquid to the vapor state is located in tubing of the second tubular element arranged in a part of said third zone of such relatively low heat intensity that injury to such tubing

will be minimized even though containing deposits of solids or scale; and means for restricting shifting of said solid or scale-deposit zone including the location of said third tubular element functioning as a superheater in such manner that the quantity of heat absorbed per unit of weight of vapor passing therethrough and being superheated is substantially constant and means for controlling the application of heat to the tubular elements so as to keep the temperature of superheated steam leaving the third tubular element substantially constant.
